(57) CLAIM

The ornamental design for a real estate sign, as shown and described.

DESCRIPTION

FIG. 1 is a perspective view of a real estate sign of my new design;

FIG. 2 is a front elevational view of the real estate sign of FIG. 1, the back elevational view being a mirror image thereof;

FIG. 3 is a left side elevational view of the real estate sign of FIG. 1, the right side elevational view being a mirror image thereof; and,

FIG. 4 is a top plan view of the real estate sign of FIG. 1. The undisclosed bottom is flat and unornamented and forms no part of the claimed design.
